US0D1056183S

(12) **United States Design Patent** (10) **Patent No.:** **US D1,056,183 S**
(45) **Date of Patent:** **** Dec. 31, 2024**

(54) **FILTER**

(71) Applicant: **Ningbo Woofun New Material Technology Co., Ltd**, Ningbo (CN)

(72) Inventor: **Zefeng Hu**, Cixi (CN)

(**) Term: **15 Years**

(21) Appl. No.: **29/856,236**

(22) Filed: **Oct. 12, 2022**

(30) **Foreign Application Priority Data**

Jun. 28, 2022 (CN) 202230401040.2

(51) **LOC (14) Cl.** **23-04**

(52) **U.S. Cl.**

USPC **D23/365**

(57) **CLAIM**

The ornamental design for a filter, as shown and described.

DESCRIPTION

FIG. 1 is a front, right and bottom perspective view of a filter, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the filter that form no part of the claimed design.

1 Claim, 8 Drawing Sheets
